FIRE ALARM SYSTEM

Orville E. Tendall, Hopkins, Minn., assignor of
one-half to Severt L. Tendall, Northfield, Minn.

Application February 24, 1948, Serial No. 10,299

5 Claims. (Cl. 73—432)

1

This invention relates to fire alarm systems for general home use, whether in city or country, and which will also serve to protect industrial plants, business property and public buildings.

Much work has been done in the field of fire alarm systems, but it has resulted in too much complication and expense, to be adaptable for general use. Fire alarm systems of the pneumatic type, heretofore constructed, have included a small bore metallic tube extending in the form of a loop over the area to be protected; and connected with a device having one or two flexible diaphragms with contacts, completing an electric circuit, resulting in an alarm; when pressure, due to temperature rise in air in tube, causes deflection of diaphragm. These systems have been provided with bleeder vents adjacent to the diaphragms, to permit air to be discharged from the system to offset air pressure increase, due to changes in temperature, such as ordinarily occur. Also, a section of the tubing may be located over steam heating pipes, which, at times, may have a similar effect on the air pressure in the tube. To take care of these conditions, without sounding an alarm and so that the system is indicative only of fire conditions, has resulted in complicated and expensive construction in addition to expensive diaphragm construction. With such delicate construction, small tubing is necessarily employed, and which is readily dented, broken or corroded and rendered inoperative. Heat insulation has been applied to such tubing, to protect it against ordinary temperature changes and other fluctuations not indicative of fire, and to protect tubing against denting and bending. Such insulation adds greatly to the expense and to the difficulty in making connections.

One object of my invention is to provide a fire alarm system for home and general use, with a simple and not-expensive fluid pressure responsive device with considerable latitude, still without complications, so changes in temperature which ordinarily occur or heats of lesser duration do not cause alarm to be sounded, but only conditions indicative of fire result in said alarm.

Another object of my invention is to provide a fire alarm system for home and general use of pneumatic type, employing a metallic tube of substantial bore, which is therefore not readily rendered inoperative by denting, breaking or corroding, and subjects a considerable volume of air to heat, and which may but need not be looped over area to be protected.

Another object of my invention is to provide a fire alarm system for home and general use,

2

which is adapted to be connected to any fire box and/or alarm system, to provide a whole metropolitan area with a completely automatic alarm system.

5. Other objects will be apparent from the description and appended claims.

For a full disclosure of my invention, reference is made to the description following and to the drawing, in which—

10. Fig. 1 is a view showing diagrammatically my pneumatic tube fire alarm system, with a supply of chemical available for extinguishing a fire, and employing an electrical alarm device.

Fig. 2 is a view of a mechanical alarm device, which can be employed with the same system.

Fig. 3 is a view of mechanism, which can be employed with the same system, to operate a more powerful mechanical long sounding alarm device.

20. Fig. 4 is a sectional view, on enlarged scale, of a small tube and plunger employed to actuate any of the different alarm devices.

Referring now to the several figures of the drawing, the reference character 10 indicates a 25 metal tube extending over the area to be protected. This extends over the area in a horizontal plane, in a manner shown for convenience as if in a vertical plane in the drawing. This tube is preferably of copper, because of the

30 good conductivity of that metal, in quickly transmitting heat to the air within the tube and causing the air to expand. In protecting the average dwelling, an arrangement of tubing as shown generally in Fig. 1 installed in the attic and in the basement, will usually suffice, as the balance of the house ordinarily consists of plastered walls.

It is of course easily arranged to suit any and all requirements, whether large or small; and several independent systems may be installed in the

40 same structure, and as will be later explained, can be adjusted to suit varying conditions in the areas protected by each system. The tube may be looped in circuit, but with the relatively large size of tube employed, there is no danger of the

45 tube becoming accidentally closed, as is the case with smaller tubing, which requires a looped circuit to insure an alarm. The tube therefore usually has an end closure 11. The tube may be secured in any convenient manner, such as

50 nailed pipe clamps, employed by plumbers and electricians. The indicator end 12 of the tube is adjustably mounted on a panel 13 by clamps 14.

Unto this end of the tube and in line therewith, is mounted a small tube 15, with a plunger 16 attached to a stem 17. This tube 15 is preferably

55

of precision tubing stock and of stainless steel, so there will be no corrosion. It is small in size relative to the area protecting tube. It has therefore little frictional resistance, and is responsive to a considerable extent to any increase in volume requirement of heated air in the larger tube protecting the area. The plunger 16 has two leather cups 18, which may also consist of other types of packing. The space 19 between these cups is filled with a grease of proper consistency, to keep the cups or packings from becoming hardened and also to lubricate walls of the tube 15. Reducing mountings 20 and 21, respectively, provide for transition between large tube and small tube and between small tube and plunger stem, the latter being guided in direct line motion by said mounting 21. The mounting 20 is commonly soldered or brazed, while the mounting 21 is screw threaded to make it easy to remove and examine the plunger 16. An adjustable contact 22 is screw threaded mounted on said stem 17. This consists of two parts as shown so as to provide thread locking action. In addition to the adjustment provided for by clamps 14 on panel 13, this contact 22 provides for further fine adjustment.

Referring now particularly to Fig. 1, which includes an electrical alarm device, and which is the most common installation, an alarm 23 and a source of electricity 24 is provided. The alarm 23 may be a bell or buzzer and may even in some cases be a light. The source of electricity 24 may be a battery, where electric wiring is not present, but in most cases will be the usual bell transformer joined to the electric wiring. To provide a circuit and energize the alarm, a bell crank lever 25 is pivotally mounted on a panel 26. A contact 27 is provided on the panel and a contact 28 is provided on the bell crank lever. By moving the bell crank lever so that two contacts touch, a circuit is made through the pivoted mounting and the short arm of the bell crank lever. An insulation splice 29 may be provided in the long arm of the bell crank lever, to obviate any flow of electricity to or from the alarm device. With said electrical alarm, the apparatus is preferably positioned as shown in Fig. 1, since the normal and out-of-contact position is assumed by gravity. It may however be made equally as operable in any other position. A stop peg 30 provides for the normal position of the bell crank lever 25; and a tension spring 31 stretched between the bell crank lever and a bracket 32, has an adjusting screw 33, by which the required tension in the spring is provided. It will be observed that the bell crank lever 25 has a relatively rather long arm, upon which the plunger stem contact 22 operates, when volume of air in system increases due to temperature increase. This added leverage is not needed for force to operate an electrical alarm, but it provides for greater latitude of movement, relative to movement of short arm, to complete a contact. This provides for a considerable amount of free travel of the plunger, without contacts completing a circuit, resulting in an alarm. This construction therefore, can take care of fluctuations in volume of air, due to normal temperature changes and to temporary conditions like the opening of a furnace door, and does not cause an alarm to be sounded except under fire risk conditions. The different adjustments provide for proper setting of apparatus for the particular case according to pre-determined values of volume increase. There is space adjustment

and spring loading adjustment. Space adjustment is accomplished by shifting indicator end of tubing backward or forward and clamping, and then supplementing by the finer screw threaded adjustment at end of plunger stem. The tension spring acting on long arm of bell crank lever, provides great range of adjustment by spring loading. By these different provisions, any required adjustment can be attained. A supply 34 of chemical, in suitable cartons or containers, is stationed on a shelf or convenient spot, so it may be readily available to extinguish a fire. Any kind of chemical employed for the purpose or any kind of fire extinguisher may be used. A simple mixture, for example, generating carbon dioxide may be used. This is easily applied by throwing on in handfuls.

Referring now particularly to Fig. 2, which includes a mechanical alarm device, I provide in lieu of electrical contacts, a pair of sears 35 and 36 mounted on a panel 37. The top sear 35 is pivoted from the panel at one end, and has a stiff pivotal link 38 at the other end, connecting it to the short arm of a bell crank lever 25. An engaging notch 39 of the sears, it will be noted, is slightly off a right angle, so as to smoothen the action to disengage the sears. A spring 40 is attached to one end of the sliding sear 36, and a connection 41 is made between the other end of the sear and a release of a mechanical alarm device. This alarm device may be an alarm clock or any other spring wound or weight operated device. It will be observed, that the other elements of the system are the same as employed for the electrical alarm device. The bell crank lever in this case, besides allowing for free travel, also makes use of mechanical advantage of the longer lever arm in disengaging the two sears. As to position, the apparatus is preferably positioned as shown in Fig. 2, since it is a natural position for the operation of the sears due to gravity. It can however be made equally as operable in any other position, by proper confinement and spring positioning of sears.

Referring now particularly to Fig. 3, which shows a heavy duty mechanical alarm device. To protect country school houses and town halls, it is necessary to actuate an alarm, which will be heard over a large area for a considerable time, in order to bring help and save the building from destruction. In school houses, where usually fires must be banked at night to last until morning, there is considerable danger of fire. Likewise in town halls, that are used only occasionally, there is danger of fire from stove or furnace; and with both town halls and school houses, there is danger of fire from grass and forest fires and by vandals. A long distance alarm is ordinarily necessary, and if electricity is not available so a motor driven siren can be used, it must be by mechanical means. Some sirens may be operated by storage batteries, but these are not very practical to maintain in such location. A mechanical alarm requires the aid of some mechanism, to produce power by spring or by weight to operate it. A gong 42, for example, may be operated by release of a weight 43, suspended by a chain or cord 44 from a drum 45, turning a train of gears 46, which turn a cam 47, which actuates a beater 48 on the gong 42. The release of the weight 43 may be accomplished by a dog or latch 49, to which is attached the mechanical connection 41 of

Fig. 2. To make it possible for the apparatus to continue the alarm for some time, it may be located in the belfry and provide for movement of the operating weight 43 from there to the ground floor. If electricity is available, a powerful and far reaching motor-driven siren can of course be set in operation, by contacts forming a circuit, as shown in Fig. 1. Besides such isolated structures as above referred to, it may be desirable in an industrial plant to use my system and a powerful alarm; rather than depend entirely on a watchman or a chance passer-by. Also, in such plants the system may be joined with a circuit to also give indication in the city fire station or to an A. D. T. office or the like. The system may be used to protect an entire area of homes and structures in such manner, by each being joined by circuit to give indication at a central fire fighting source.

From the foregoing, it will be apparent just how the system is constructed and also in general how it operates. The system is assembled at atmospheric pressure, so there are no complications in regard to installation. By use of the several adjustments, the apparatus is readily set for the particular case according to pre-determined values of volume increase. As previously referred to, there may be different areas in the same structure, that have such varying conditions, that a separate system is needed for each area. In a hot forge shop for example, conditions are different than in balance of a plant. By recording of temperatures in the area to be protected, and making use of pre-determined values of volume increase, the apparatus is set accordingly to be indicative of fire in the area. If electric, several areas may be wired to the same alarm, or have separate alarms for each area, and the alarm may be at a distant point outside the area. The apparatus has great latitude in that it has considerable free travel range, in which the normal conditions peculiar to the particular area may be taken care of, so changes in temperature which ordinarily occur or heats of lesser duration do not cause alarm to be sounded, but only conditions indicative of fire result in such alarm. This is made possible by the use of rather large diameter area protecting tubing and a small diameter cylinder for the signal initiating device. A considerable volume of air in the area protecting tube is subjected to heat in case of fire, and its increased volume requirement applied to the small diameter cylinder, causes considerable movement of the plunger. This gives opportunity for adjustment, so that fluctuations from ordinary causes are well within the range of travel of the plunger when bringing about a fire alarm. Because of this, a simple system without complication can be provided. The size of the area protecting tubing may be varied with, however, the same indicator apparatus. Where a more sensitive system is required, a still larger diameter area tube may be used. It may be used to indicate other than fire conditions and cause ventilators to be opened and other precautions taken, to prevent explosions and spontaneous combustion, such as occur in flour mills, grain elevators, coal chutes and hay barns. It may even be used to indicate variation in temperature conditions within large food locker and refrigeration plants. The tubing may be submerged in material like grain or slack coal, to indicate any damage or danger due to heating. It may also be used in cargos in holds of ships, and in that and other cases, may be

equipped with an alarm or a graph recording device or both. All in all, the system is simple, is not easily damaged and has substantial latitude of adjustment.

5 While I have shown and described a preferred form of my invention, it is obvious that many changes, which are within the scope of my invention, will be apparent to those skilled in the art. I therefore desire to be limited only by the scope of the appended claims.

10 What I claim is:

1. In a system of the character described; the combination of a closed metal tube of substantial bore, said tube extending over area to be protected, said tube being in communication with a relatively small cylinder, a plunger with a stem in said cylinder serving as a signal initiating device, said plunger having a plurality of lubricated packings and constructed so as to be responsive to interior fluid pressure of tube, an adjustable thrust member on end of said stem, a mechanical alarm device, spring loaded compound leverage adapted to actuate said mechanical alarm device, due to sudden unusual increase of fluid pressure in said tube, by disengaging a sliding sear from a pivoted sear by raising said pivoted sear, said sliding sear being loaded at one end by a tension spring and its opposite end having a connection to a release of said mechanical alarm device.
2. In a system of the character described in claim 1, with a mechanical alarm device, comprising a gong, a beater, a cam oscillating said beater, a train of gears turning said cam, a drum co-axial with the furthermost of said gears, a weight suspended from said drum by winding its suspending member around said drum, and a release acting on said gears, all co-operating to actuate said alarm device.
3. An actuator, comprising a cylinder of relatively small diameter, a plunger in said cylinder having a plurality of lubricated packings, a stem attached to said plunger, a cap on one end of said cylinder perforated for said stem, an adjustable thrust member screw threadedly attached to the outer end of said stem and consisting of two parts for thread locking action, a bell crank lever pivoted for engagement by said thrust member, said lever having its longer arm engaged by said thrust member and providing mechanical advantage and greater latitude of movement relative to movement of short arm, a spring positioned to provide resistance to movement of said lever by said thrust member and having means for adjusting said spring, a stop for limiting movement of said lever by said spring, means for positioning said cylinder relative to said lever subject to closer adjustment by said thrust member, and a mounting connecting said cylinder at the end opposed to its stem to an area protecting pneumatic tube of substantially greater diameter than said cylinder, whereby plunger in said cylinder is rendered sensitive to any increased volume requirement of air in said tube due to temperature increase according to size of said tube relative to said cylinder, and by varying mechanical advantage of said bell crank lever, cause different devices to be operated subject to said adjusting and positioning means to allow free travel according to pre-determined values of volume increase without causing operation of said devices.
4. An actuator, comprising a cylinder in communication with an area protecting pneumatic tube of substantially larger diameter, a plunger in said cylinder having a plurality of packings

and with space for lubricating material between said packings, a stem attached to said plunger, an adjustable thrust member on end of said stem, a spring loaded bell crank lever positioned for engagement by said thrust member and to actuate different devices, and clamping means to adjustably position said plunger relative to said bell crank lever, which means together with said adjustable thrust member and said spring loading of bell crank lever provide for great latitude of adjustment to permit substantial free travel of said plunger without actuation by said thrust member within range of ordinary temperature changes or happenings in protected area, but in case of sudden unusual rise of temperature due to fire to cause said actuator to act in accordance with pre-determined values to which it has been adjusted to actuate said devices.

5. An actuator, comprising a cylinder, a plunger with a stem in said cylinder, said plunger having a plurality of lubricated packings, an adjustable thrust member on end of said stem, a spring loaded compound leverage arranged for engagement by said thrust member to actuate

different devices and means for connecting said cylinder in communication with an area protecting pneumatic tube, said cylinder being of relatively small diameter compared to said tube, whereby sensitiveness to variations in pressure in said tube is exhibited by substantial movement in said plunger, so as to permit adjustment for free travel without actuating said devices except in cases of unusual changes of pressure indicating danger.
